UNITED STATES PATENT OFFICE.

JOHN B. SEMPLE, OF SEWICKLEY, PENNSYLVANIA.

FUSE.

1,369,476.

Specification of Letters Patent. Patented Feb. 22, 1921.

Application filed May 20, 1920. Serial No. 382,933.

To all whom it may concern:

Be it known that I, JOHN B. SEMPLE, residing at Sewickley, in the county of Allegheny and State of Pennsylvania, a citizen 5 of the United States, have invented or discovered certain new and useful Improvements in Fuses, of which improvements the following is a specification.

My invention relates to delay-acting detonating fuses, such as are used in shells for artillery, and consists in novel means for effecting delay.

The invention is illustrated in the accompanying drawings. Figure I shows in longitudinal medial section the fuse member as it is applied to a shell; Fig. II is a like view to larger scale of a portion of the structure shown in Fig. I.

The fuse is, as is customary, carried in a stock 1, adapted to be screwed into position in an opening formed in the wall of a shell. It includes as its essential elements a percussion cap or primer 2, with means for firing it, a detonator 3; and, in addition, a 25 third element, not essential though ordinarily present, a booster charge 4. The means for firing the primer include hammer and anvil members 5 and 6, one ordinarily secured permanently against movement 30 within the stock, the other secure under all ordinary stresses, but with securing means, such as shear-pin 7, rendered ineffective under the extreme shock incident to the firing of the shell from a gun, leaving hammer and 35 anvil members relatively movable, to the end that on impact (when the flying shell strikes) the primer will be fired. These features are old, and the exemplary presentation which the drawing affords will suffice. It will be understood that the fuse 40 to which my invention is applicable is one in which the primer is fired on impact, but as to the arrangement of and the arming of the firing means—these are matters which 45 may be varied at will, as the one who practises my invention may prefer.

A passageway leads from primer to detonator. In ordinary practice this is merely an open canal, through which the flash of 50 the primer is projected, to impinge upon and fire the detonator, without appreciable delay, and it is at this point that the peculiarity in structure resides, in which my present invention consists. I screen the detonator behind a barrier, and I provide 55 means, effective only after a delay, by which

the barrier may either be burned through or melted through or heated through, to effect ignition of the detonator beyond. Such means constitute in effect a "relay" for the 60 primer—a relay, ignited by the primer, which, continuing to burn during a relatively long interval of time, will ultimately surmount the barrier, and in one manner or another of those suggested, effect ignition 65 of the detonator.

The barrier which screens the detonator is in the drawings indicated at 8; it may be formed of celluloid, for example, and in that case, being ignited, it will burn away 70 and expose and indeed impart ignition to the detonator; it may be a thin septum of lead, or of another metal or an alloy of low melting point, and in that case it will under continued impact of a jet of flame melt 75 away, exposing the detonator; or, again, the barrier, lying close upon the substance of the detonator, may be formed of copper or of other metal of good heat conductivity, to the end that the heat from the relay 80 communicated through the barrier, even though it does not destroy the barrier, will still ignite the detonator beyond. The thickness of the barrier is the factor which, other things being equal, will determine the duration of delay; if the barrier be thin, the delay will be short; if thick, it will be long.

The relay for the primer has this characteristic: it affords heat or flame, which being for a prolonged interval of time exerted 90 upon the barrier covering the detonator, penetrates it. As I have said, in the usual fuse construction an open duct leads from primer to detonator. In the embodiment of the invention shown in the drawings a 95 relay charge of suitable material, conveniently black powder, is arranged between primer and detonator where ordinarily the open duct is found. This relay charge receives the flash of the primer, and, ignited 100 thereby, affords a long enduring flame which, continuing to play upon the barrier, penetrates it at length and ignites the detonator. This charge of black powder is particularly constructed and arranged to effect the end; and, while in broader aspect 105 my invention is not limited to this particular relay, it still embodies specific features of invention.

The normal flashway from primer to detonator is here enlarged, into a chamber in which is set a body 9 of compressed black

powder. The chamber preferably is contracted at the end adjacent the detonator to a narrow orifice 13. Through the center of this body 9 and in line between primer and detonator and continuous with orifice 13 is a duct which is filled with a body 10 of loose or relatively uncompressed black powder. The compound body of powder 9, 10 does not extend all the way to the barrier 8 which faces the detonator; there is an interval between, and preferably the normal flashway is there enlarged, affording an "overflow space" 11, for the gases generated by the burning of the relay charge. The body of loose powder 10 may be suitably confined, as by a cork 12 set in orifice 13, to prevent escape into space 11. The cork 12 will be blown out, leaving the passageway free, on the burning of the body of powder 10.

The composition of the detonator may be such as is preferred; its essential characteristic is that it will detonate under heat or flame, penetrating barrier 8 from relay charge 9.

The operation is easily understood. On impact of the shell the primer 2 is fired. The flash of the primer, impinging on the body 10 of loose powder, ignites it. This body 10 is immediately consumed; in its consumption cork 12 is driven into space 11, a passageway to the detonator is opened, and the body 9 of compressed powder is ignited. The body 9 burns gradually, and during a sufficiently prolonged period the burning of body 9 affords a jet of flame which escaping through orifice 13 impinges upon the barrier 8 which faces detonator 3. Penetration of the barrier ensues (either bodily penetration of the flame, in consequence of the burning or the melting of the barrier, or penetration of heat alone), after an interval predetermined in the selection of material for and the proportioning of the barrier 8. It is this interval of delay which constitutes the fuse a delay-acting fuse.

I claim as my invention:

1. In a delay-acting detonating fuse, the combination of a primer, a detonator, a septum screening the detonator from immediate ignition by the flame from the primer, and a gradually combustible relay receiving ignition from the primer and in course of burning delivering upon the septum a continuing flame, substantially as described.
2. In a delay-acting fuse detonating upon impact the combination of a primer fired by impact of the shell which carries it, a det-

onator, a barrier screen between detonator and primer, a gradually combustible relay between screen and primer, said relay exposed to the flash of said primer and in course of burning delivering in turn a continuing flame upon said screen, substantially as described.

3. In a delay-acting detonating fuse, the combination of a detonator; a barrier screen facing said detonator, and means for bringing to bear for a prolonged interval of time a flame upon said screen, such means including a chamber with restricted orifice, a body of compressed black powder within said chamber and having a central bore aligned with said orifice filled with loose black powder, and means for imparting ignition to the body of loose powder within said bore, substantially as described.

4. A delay-acting detonating fuse including in combination a primer and a detonator, a barrier screen facing the detonator, and a relay charge including a body of compressed black powder, with a bore through it, and a body of loose black powder filling such bore, said bore exposed on one side to the flash of the primer and opening on the other side to the barrier-faced detonator, substantially as described.

5. A delay-acting detonating fuse including in combination a detonator, a barrier screen facing said detonator, means for bringing to bear for a prolonged interval of time a flame upon said screen, such means including a chamber having a contracted orifice arranged opposite said barrier-faced detonator, combustible material within said chamber, and means for imparting combustion to the body of material within said chamber, substantially as described.

6. A delay-acting detonating fuse including in combination a primer, a gradually combustible body affording a flame of prolonged duration arranged to receive the flash of the primer, and a detonator screened by a barrier gradually yielding to penetration of a detonator-igniting impulse inherent in flame and arranged to receive throughout the period of burning the flame of the said combustible body, substantially as described.

In testimony whereof I have hereunto set my hand.

JOHN B. SEMPLE.
